UNITED STATES PATENT OFFICE.

JOSEPH ZUCKERMAN, OF NEW YORK, AND PINCUS ZUCKERMAN, OF BROOKLYN, NEW YORK.

LOCK.

1,413,450.

Specification of Letters Patent. Patented Apr. 18, 1922.

Application filed October 6, 1919. Serial No. 328,642.

To all whom it may concern:

Be it known that we, JOSEPH ZUCKERMAN and PINCUS ZUCKERMAN, citizens of Poland, residing at New York and Brooklyn, respectively, in the counties of New York and Kings, respectively, and State of New York, have invented new and useful Improvements in Locks, of which the following is a specification.

10 This invention relates generally to the class of locks for doors and means for operating and controlling the same.

In the forms of locks now in general use, it is possible to spring the bolts from the keepers by the use of a "jimmy" or other tools of this character and it is therefore one of the principal objects of this invention to produce a lock which will overcome this objection by constructing the same in such a manner as to render it substantially proof against opening by means of these tools.

Another object of the invention is to provide a lock employing independent bolts arranged for sliding movement in the same plane, at right angles to each other, their paths of movement intersecting each other whereby one of said bolts may be projected to a position behind the other to prevent retraction of the same.

30 A further object of the invention is to provide a lock having key operating means disposed at one side thereof for independently controlling the movements of the separate bolts, and knobs disposed on the opposite side of the lock for controlling the bolts from the interior, said knobs being adapted to be normally locked by the key operating means but capable of being moved to a position for independently operating said bolts.

40 With these and other objects in view, the invention resides in the novel construction, combination and arrangement of parts more fully described and pointed out in the following description, and claims and illustrated in the accompanying drawing, in which:—

Figure 1, is a fragmentary elevation of a door and jamb with the improved lock applied thereto, as viewed from the exterior.

50 Figure 2 is a similar view looking from the interior.

Figure 3 is an enlarged elevation of the lock with the cover plate removed and parts shown in section to more clearly illustrate 55 the details of construction.

Figure 4 is a vertical transverse sectional view therethrough taken approximately on the line 4—4 of Figure 3.

Figure 5 is a detail perspective view of one of the bolts removed from the lock.

Referring to the drawing by character of reference, 10 designates a portion of the jamb of a door provided with the usual keeper opening 11, for the reception of a locking bolt. The door 12 has secured to its inner side a lock casing 13 provided with a cover plate 14 which is preferably arranged in flat contact with the door. A main locking bolt 15 is arranged for horizontal sliding movement within the casing 13 and the outer extremity 16 of the same is adapted to be projected through an opening 17 for engagement with the keeper 11 of the door jamb. The bolt 15 is provided with a row of evenly spaced rack teeth 18 which are preferably in the nature of studs projecting from one of the side faces of the same and said teeth are adapted to be engaged by a pinion 19 secured to a barrel 20, the latter being mounted for rotation within the casing. An auxiliary bolt 21 is also arranged within the casing for vertical sliding movement and is provided with a similar series of rack teeth 22 adapted to co-act with the pinion 23 secured to or formed on a barrel 24, said barrel being mounted for rotation within the casing as illustrated. It will thus be seen that when the barrels 20 and 24 are rotated, movement of the bolts 15 and 21 may be effected in either direction and normally the bolt 21 is disposed below the horizontal plane of the bolt 15 whereby the latter is free for movement in either direction. When the bolt 15 has been moved to the position illustrated in Figure 3, the auxiliary bolt 21 is projected to a position behind the same in order to prevent retraction of the same.

The means for rotating the barrels 20 and 24 are identical and a description of one of said means will therefore suffice for both. The said operating means includes a key operated, locking cylinder 25 arranged within a casing which is embedded in the door and is provided with the usual keyhole 26 arranged exteriorly of the same. Connected with the cylinder for turning movement therewith is an inwardly extending shaft 27 which is preferably enlarged and squared as at 28 adjacent the cylinder. The barrels 29

20 and 24 are provided squared openings 29 in for sliding movement, a which is preferably square 5 to mate with the opening of the sleeve 30 is provided flange 31 arranged with in the door and the op sleeve which is extended 10 surface of the casing 13, cured thereto, said knob for sliding the sleeve and turning the same to The bore of the sleeve is 15 fit the squared portion 28 the same is moved inward of a coil expansion spring being interposed between the plate 35 which covers 20 the door.

To unlock the door it is assumed that the same is locked and the bolts are illustrated in Figure 25 inserted first in the lower cylinder 25 is rotated, the barrel 24 and pinion 23 to the extent of the squared portion of the sleeve; the engagement with the rack of the sleeve causes the same to move down the horizontal plane of the door, then inserted in the upper rotation of the same in 30 35 will revolve the barrel bolt 15 from the keeper to lock the door from the used, as it is only necessary to pull outwardly on the 40 distance to disengage the squared portion of the sleeve and independent movement of the sleeve and barrel. It is that normally the spring
